UNITED STATES PATENT OFFICE.

WILLETT J. LA TOURRETTE, OF DENVER, COLORADO.

INTERNAL-COMBUSTION ENGINE.

Application filed October 2, 1923. Serial No. 666,058.

To all whom it may concern:

Be it known that I, WILLETT J. LA TOURRETTE, a citizen of the United States, residing at Denver, the city and county of Denver and State of Colorado, have invented certain new and useful Improvements in Internal-Combustion Engines; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to improvements in internal combustion engines of the type known as four cycle engines.

Those who are skilled in this art are aware that the internal combustion engines of the type under consideration have several objectionable features which reduce their efficiency and tend to make them noisy in operation. Among the objectionable features may be mentioned that at the end of the exhaust stroke, the clearance space is left filled with gaseous products of combustion which become mixed with the new charge and merely take up valuable space; that the reciprocating parts are not cushioned except on the compression stroke which causes unnecessary strains to be imposed on the bearings twice each revolution; that the present construction permits an undue amount of oil to enter the combustion chamber with the result that an excessive amount of oil is used and a large amount of objectionable carbon is formed; that the explosive mixture must be taken into the combustion chamber excessively rich in order to obtain sufficiently rapid combustion, thereby reducing the economy of operation and then a small percentage of unconsumed fuel works past the piston into the crank casing and is lost.

It is the object of this invention to produce an engine in which the above-referred to objectionable features will not be present.

My invention, briefly described, embodies a construction in which each cylinder has two spaced pistons connected by a rigid member which passes through a partition that divides the space between the pistons into two chambers. Means are provided for admitting air into these chambers which will be compressed and serve to cushion the reciprocating parts at the end of each stroke.

Means is also provided for admitting the air that was employed to cushion the inward or downward stroke into the explosion chamber, thereby replacing the inert gases with air.

The invention can be most clearly explained by making reference to the accompanying drawing in which one embodiment of my invention is shown, and in which the single figure shows a vertical transverse section passing diametrically through one of the cylinders.

Numeral 1 designates one of the cylinders of which there may be any number. The cylinder is divided into an upper or explosion chamber A and a lower compression chamber B by means of a partition 2 that is held in place by suitable bolts 3. The lower portion of chamber A is surrounded by an annular chamber C which communicates with it through a plurality of ports 4. A water jacket D surrounds the upper portion of chamber A. A cylinder head 5 fits on top of the cylinder and has the usual spark plug 6. Intake and exhaust valves 7 and 8, respectively, correspond to the ordinary intake and exhaust valves and are operated from the cam shaft 9 through the medium of any standard mechanism. A crank shaft is rotatably mounted in the crank casing 10 and the crank pin 11 is connected by means of a connecting rod 12 with the wrist pin 13 of piston 14. Piston 14 reciprocates in chamber B and is connected by means of a rod 15 with the working piston 16 that is mounted for reciprocation in chamber A. The length of rod 15 is such that when the crank pin is at the lower dead center position, piston 16 will approach very close to the upper surface of the partition 2. When piston 16 is in its lowermost position, its upper edge will be a short distance below the upper edges of ports 4 so that passageways connect chamber C with chamber A. A port 17 connects chamber B with the outside atmosphere. The location of port 17 is determined by the amount of compression that is desired on the upward stroke of piston 14. The farther the port 17 is from the partition 2 the greater will be the volume of air that will be entrapped and compressed on each upward stroke and the greater will be the cushioning effect obtained. Chamber C is connected with the atmosphere through a passageway 18 which is controlled by a valve 19 that opens inwardly

and is normally held in closed position through the action of the spring 20 and is held in open position during the upward stroke by means of cams 21. A butterfly valve 22 serves as a means to regulate the amount of air introduced during each stroke. A plug 23 closes the opening over valve 19. Passages 24 and 25 extend from the lower end of rod 15 to a point such distance above the piston 14 that the opening 25 will extend above the partition 2. The suction due to the diminished pressure in chamber C below piston 16 during the upward stroke will draw lubricating oil through the passages 24 and 25 and spray the same on the cylinder walls.

The operation of my engine is as follows: Let us assume that the parts are in the position shown in the drawing and that the crank shaft is then rotated in a clockwise direction. The pistons 14 and 16 will be moved in an upward direction. Let us further assume that this is the exhaust stroke and that therefore exhaust valve 8 is open. During every up stroke of the pistons, valve 19 is held in open position by means of cams 21. As piston 14 passes the port 17 the air above the piston will be compressed, which will serve to cushion the parts and to assist in bringing the parts to a stop. On the downward stroke, which will be the intake stroke, valve 8 will be closed and intake valve 7 will be open. The valve 19 will always be in closed position during the downward movement of the pistons. As the pistons move downwardly the compressed air above piston 14 will expand and assist in accelerating the parts and at the same time the air below piston 16 will be compressed. When piston 16 has traveled downwardly to such a distance that its upper edge will uncover the ports 4, air from chamber C will rush into the chamber A and mix with the explosive charge. The second upstroke compresses the charge and on the second downstroke the charge is exploded and delivers its power. When the pistons reach their lowermost position on the power stroke, exhaust valve 8 will open and permit the gases to leave the explosion chamber and at the same time air from chamber C will rush into the explosion chamber and drive the gaseous products of combustion out. The air which is admitted into the combustion chamber A assists greatly in cooling the parts and prevents, to a great extent, pre-ignition. The partition member 2, besides its other function, prevents an excess of oil from passing into chamber A and prevents any unconsumed fuel from passing into the crank casing. Any fuel that does pass into the space below piston 16 will be mixed with the air in chamber C and returned to the combustion chamber. By manipulating the valve 22 the amount of air

admitted to chamber C can be regulated to suit the conditions.

The drawing shows one embodiment of my invention and it is understood that such changes and alterations may be made as may be necessary without departing from the invention covered by the claims.

Having now described my invention, what I claim as new is:

1. In an internal combustion engine; a cylinder; a partition member intermediate the end of said cylinder, said partition member having an opening; a crank casing connected to the lower end of said cylinder; a crank shaft rotatably mounted in said casing; a piston reciprocally mounted in each end of said cylinder, said pistons being connected by means of a rigid bar passing through the partition member; a crank pin on the crank shaft; means comprising a rod for connecting said crank pin to the lowermost piston whereby the rotation of the crank shaft will reciprocate the pistons; means for admitting air into the space between the pistons and the partition member as the pistons move away from said member; means for compressing air when the pistons move towards the partition member; and means for controlling the amount of air that enters the space between the upper piston and the partition member.

2. In an internal combustion engine; a cylinder; a partition member intermediate the end of said cylinder, said partition member having an opening; a crank casing connected to the lower end of said cylinder; a crank shaft rotatably mounted in said casing; a piston reciprocally mounted in each end of said cylinder, said pistons being connected by means of a rigid bar passing through the partition member; a crank pin on the crank shaft; means comprising a rod for connecting said crank pin to the lowermost piston whereby the rotation of the crank shaft will reciprocate the pistons; means for admitting air into the space between the pistons and the partition member as the pistons move away from said member; means for compressing air when the pistons move towards the partition member; means for controlling the amount of air that enters the space between the upper piston and the partition member; and means for permitting the air from the lower side of the upper piston to pass into the chamber above the piston when the latter is near its lowermost position.

3. In an internal combustion engine; a cylinder; a partition member intermediate the end of said cylinder, said partition member having an opening; a crank casing connected to the lower end of said cylinder; a crank shaft rotatably mounted in said casing; a piston reciprocally mounted in each end of said cylinder, said pistons be-

ing connected by means of a rigid bar passing through the partition member; a crank pin on the crank shaft; means comprising a rod for connecting said crank pin 5 to the lowermost piston whereby the rotation of the crank shaft will reciprocate the pistons; means for admitting air into the space between the pistons and the partition member as the pistons move away from said 10 member; means for compressing air when the pistons move towards the partition member; means for controlling the amount of air that enters the space between the upper piston and the partition member; 15 and means for permitting the air from the lower side of the upper piston to pass into the chamber above the piston when the latter is near its lowermost position, the bar which connects the pistons being provided 20 with an oil passage extending from a point below the lower piston to a point which is well above the partition members when the pistons are in their uppermost position.

4. An internal combustion engine comprising, in combination, a cylinder; a partition member within said cylinder dividing the same into an upper and a lower compartment, said partition having a central opening; a piston in each of said compartments; a bar connecting said pistons and 25 passing through the opening in the partition; a chamber surrounding the cylinder directly above said partition member; an air inlet to said chamber; a valve in said inlet; means for opening said valve and 30 maintaining it open during each upward stroke of the piston and for maintaining said valve closed during each downward stroke of the pistons, the cylinder wall between said chamber and the piston chamber 35 having a plurality of openings whose upper portions extend above the upper edge of the piston when it is in its lowermost position; and a control valve in said air inlet. 40

In testimony whereof I affix my signature.
W. J. LA TOURRETTE.
